CLAIM

The ornamental design for a archery target stand, as shown and described.

DESCRIPTION

FIG. 1 is a perspective view of the preferred embodiment of the archery target stand incorporating my new design.

FIG. 2 is a front view of FIG. 1.

FIG. 3 is a rear view of FIG. 1.

FIG. 4 is a top view of FIG. 1.

FIG. 5 is a bottom view of FIG. 1.

FIG. 6 is an end view of FIG. 1 with the opposite being a mirror image.

FIG. 7 is a perspective view of the first alternate embodiment of the archery target stand incorporating my new design.

FIG. 8 is a front view of FIG. 7.

FIG. 9 is a rear view of FIG. 7.

FIG. 10 is a top view of FIG. 7.

FIG. 11 is a bottom view of FIG. 7; and,

FIG. 12 is an end view of FIG. 7 with the opposite end being a mirror image.

The archery target stand is for holding an upright archery target.
